UNITED STATES PATENT OFFICE.

CHARLES D. SHAFFER, OF ESCATAWPA, MISSISSIPPI.

WEATHER-STRIP.

1,345,409.

Specification of Letters Patent.

Patented July 6, 1920.

Application filed March 12, 1918. Serial No. 221,976.

To all whom it may concern:

Be it known that I, CHARLES D. SHAFFER, a citizen of the United States, residing at Escatawpa, in the county of Jackson and State 5 of Mississippi, have invented certain new and useful Improvements in Weather-Strips, of which the following is a specification.

This invention relates to weather strips and has for its primary object to provide a 10 weather strip for use primarily on the under side of swinging doors and windows and when such door or window is closed to contact with the sill thereof and form a closed joint therewith to prevent the entrance of rain or wind.

A further object of the invention is to provide a weather strip of metal designed to be partly seated within a groove in the underside of a swinging door or window and 20 supported in such position to swing to and from the bottom of the door and maintained when out of use against the bottom of the door by suitable resilient means and adapted to coöperate at its end or ends with a 25 lug or lugs on the frame when the door or window is closed for the purpose of depressing or rocking the weather strip into contact with the sill and so form a tight joint.

With the above objects in view, the invention 30 consists in the novel construction, combination and arrangement of parts herein-after described, pointed out in the appended claims and illustrated in the accompanying drawings, in which:—

Figure 1 is a vertical sectional view through the lower portion of a door and the door sill with the improved weather strip in 35 position and shown in contact with the door sill to prevent the entrance of air or water into the room.

Fig. 2 is an elevation partly in section on the line 2—2 of Fig. 1.

Fig. 3 is a sectional view through the lower portion of the door with the weather strip in elevated position and out of use.

Fig. 4 is an exterior view of one corner of a door and door frame with the weather strip applied and in use, and,

Fig. 5 is a detailed perspective view of 50 one end of the weather strip showing the means for depressing or rocking the strip into its operative position.

In the drawings, 10 indicates a swinging door and 11 the sill therefor, the door, being 55 mounted on hinges to swing in a frame 12, has formed in its bottom edge a groove 13

extending the full width of the door. Within the groove 13 is seated a weather strip 14 formed of a strip of sheet metal as long as the door is wide and bent into U-shape 60 in cross section as shown in the drawings, one side 15 being wider or projecting a greater distance beyond the bend 16 than the other side 17. Through the side of the strip 17 near the bend 16 are a series of perforations 18 spaced apart to receive fastening screws 19 that hold the strip in position on the bottom of the door. For convenience of inserting the screws perforations 20 are formed in the side of the strip 15 in line 70 with the perforations 18 to permit insertion of a screw driver for forcing the screws into the door. The screws 19 do not secure the strip rigidly in place, but project a short distance into the slot 13 so that the strip 75 will rest upon the heads of the screws and be supported thereby, a short space being left between the strip and the bottom of the groove to permit the strip to rock freely on the screw heads, said strip being held 80 in a substantially horizontal position as in Fig. 3 with the part 15 in contact with the underside of the door by two or more flat or other shaped springs 21, each secured at one end to the bottom of the groove 13 and 85 bearing at its other end on the curved portion 16 of the strip serving thereby to depress said portion and raise the outer free edge of the part 15 that when in use contacts with the sill 11. When the door is 90 swung away from the sill 11, the springs 21 hold the part 15 in contact with the bottom of the door and so permit the door to swing freely, but when nearly closed, fingers 22 on one or both ends of the part 15 95 of the weather strip engage under a lug or lugs 23 secured to the door frame and cause said weather strip to swing downwardly until the outer edge of the part 15 bears upon the sill 11, thus forming a perfect flashing 100 for the bottom of the door and keeps wind and water from blowing under the door into the building.

In applying the strip to a door having a groove 13 in the bottom, the narrower part 105 17 of the weather strip is seated in the groove 13 after the springs 21 have been placed in position, and the screws 19 driven in sufficiently far to hold the strip in place and the springs under tension, which as 110 previously stated, bear upon the curved portion 16 of the weather strip and so raise the

outer free end of the part 15 against the underside of the door. The lug or lugs 23 are now fastened to the door frame just above the door sill and in such position that 5 the forward beveled end thereof will be in position to engage the finger or fingers 22 on the weather strip and depress the latter against the sill 11 when the door is fully closed. When the door is opened, these 10 fingers swing away from the lugs and permit the springs 21 to again return the weather strip to its inoperative position.

What I claim is:

1. In combination with a closure having 15 a groove in an edge thereof, a weather strip comprising narrow and wide elements spaced apart and connected at corresponding edges, the connecting portions being rounding, the wide element overlapping an edge portion of 20 the closure at one side of the groove and the narrow element and rounded connecting portion being disposed within the said groove, and fastening means connecting the narrow element with the bottom of the 25 groove to admit of the weather strip having both a tilting movement and a movement

toward and from the grooved edge of the closure.

2. In combination with a closure having a groove in an edge thereof, a metal strip 30 folded upon itself between its longitudinal edges to provide spaced narrow and wide elements and a connecting rounded portion and disposed with the narrow element and rounded connecting portion within the said 35 groove and the wide element overlapping the edge of the closure at one side of the groove, headed fastenings connecting the narrow element with the bottom of the groove and having the heads spaced from 40 the bottom of the groove to admit of the strip rocking and moving bodily toward and from the grooved edge of the closure, and springs secured in the groove and exerting an outward pressure on the narrow element 45 adjacent the rounded connecting portion.

In testimony whereof I affix my signature in presence of two witnesses.

CHARLES D. SHAFFER.
